United States Patent Office

Des. 221,731
Patented Sept. 7, 1971

221,731

BOTTLE OR SIMILAR ARTICLE

Ted L. Beaver, Roselle, Ill., assignor to Continental
Can Company, Inc., New York, N.Y.

Filed Feb. 2, 1970, Ser. No. 21,215

Term of patent 14 years

Int. Cl. D9—01

U.S. Cl. D9—40

7-10-1-

7-10-2-

FIG. 3.

FIG. 4.

FIG. 1 is an elevational view of a bottle or similar article showing my new design, the opposite side being a mirror image of the side shown;

FIG. 2 is an elevational view looking from the right of FIG. 1;

FIG. 3 is a top plan view thereof; and

FIG. 4 is a bottom plan view.

I claim:

The ornamental design for a bottle or similar article, substantially as shown.
